CLAIM

The ornamental design for a lens cover, as shown and described.

DESCRIPTION

FIG. 1 is a perspective view of a lens cover showing our new design;

FIG. 2 is another perspective view of the lens cover shown in FIG. 1;

FIG. 3 is a front elevational view of the lens cover shown in FIG. 1;

FIG. 4 is a top plan view of the lens cover shown in FIG. 1;

FIG. 5 is a rear elevational view of the lens cover shown in FIG. 1;

FIG. 6 is a bottom plan view of the lens cover shown in FIG. 1;

FIG. 7 is a right side elevational view of the lens cover shown in FIG. 1; and,

FIG. 8 is a left side elevational view of the lens cover shown in FIG. 1.

The evenly spaced broken lines shown in the figures illustrate portions of the lens cover that form no part of the claimed design.

1 Claim, 4 Drawing Sheets
